UNITED STATES PATENT OFFICE.

ARTHUR W. COLLOM, OF MEADVILLE, PENNSYLVANIA.

SIGNAL-LIGHT.

No. 853,499.

Specification of Letters Patent.

Patented May 14, 1907.

Application filed September 27, 1906. Serial No. 336,455.

To all whom it may concern:

Be it known that I, ARTHUR W. COLLOM, a citizen of the United States, residing at Meadville, in the county of Crawford and State of Pennsylvania, have invented certain new and useful Improvements in Signal-Lights, of which the following is a specification.

My invention relates to signal lights, and its principal, although by no means sole application is to the headlights of railway locomotives.

My invention belongs directly to that type of signal lamps in which a colored screen or a shade is raised by mechanical contrivances to inclose or partly surround the light-giving body.

The object of my invention is the construction of mechanism actuated by fluid pressure, usually compressed air, for raising and lowering the screen.

It is also the object of my invention to produce such mechanism having in character and function the quality of requiring no air from the source of supply unless the screen is moved, there being no pressure present in any portion of the apparatus adjacent to the screen unless the screen is in motion, or has just completed a movement into its position about or before the light.

In the use of my invention, and by reason of the preferred construction thereof herein set forth, the air is applied and then at once shut off, whether the screen is to be raised or lowered. As a consequence, no loss of power results through leakage in the apparatus or carelessness and inattention on the part of the operator, and the most economical consumption of air is attained.

The stated objects are accomplished by fashioning and associating the mechanical instrumentalities as illustrated in the accompanying drawings, of which

Figure 1 represents a front view of the reflector of a headlight or other signal lamp, and a side view of the screen-operating mechanism, the screen being in its lowered position. Fig. 2 is a top plan view, the reflector being omitted. Fig. 3 is a view similar to Fig. 1, but showing the actuating apparatus in vertical section and the screen in its raised position. Fig. 4 is an end view of the mechanism from the right of Fig. 1.

Like letters of reference are used to designate the same parts throughout the description and drawings.

The letter A refers to the reflector, in which is supported in the usual way a lamp B. From the base b of the lamp rise the twin parallel guide rods b'. The rods are perpendicular and arranged one on either side of the lamp. The screen or shade is designated by the letter C and its vertical side edges e are formed in tubular shape and adapted to engage the guide rods and to be raised and lowered upon them.

A bell crank D has its longer arm pivotally connected with the screen by the link d. The bell crank is fulcrumed upon the post d', and its shorter arm is pivotally connected with the operating rod E. Rod E has its remaining extremity pivotally coupled with a crosshead F by means of the pin f projecting laterally from the crosshead, and, consequently, rod E partakes of the back and forth movement of the crosshead. These parts will be again mentioned.

In Figs. 1 and 3 it will be noted that the bedplate G which is suitably secured to the base of the lamp, is formed with upwardly-projecting parts designated, respectively, from left to right, the cylinder block g, the guide post g' and the twin lugs g", the latter being located at the right hand end of the bedplate. In Fig. 3 it is shown that there are two hollow cylinders formed in the block g. The lower of the two and the larger is marked H, and the upper one is designated J. The piston h of the lower cylinder is secured at one end of the piston rod h', and at the other end of that rod the crosshead F is fixed. Now, it is thought to be clear that any pressure to the left of pistonhead h forces it and attached parts to the right and by means of the operating rod and bell crank raises the screen. Furthermore, if those parts thus raised are made sufficiently heavy, as I make them, they will descend by their weight as the pressure in cylinder H is relieved and will restore the parts to their attitudes illustrated in Fig. 1 when cylinder H is wholly exhausted. The piston rod h' is guided by its passage through a suitable orifice in the guide post g'.

Compressed air is applied from any convenient source of supply by means of the hose K including the three-way operating

cock k . The hose is led by pipe k' into the upper and smaller cylinder J , and by way of the communicating duct j the air enters the larger cylinder H . The duct j is opened and closed by a slide-valve j' , as best shown in Fig. 2, and the valve is connected with and operated by the sliding rod L , also guided as will be observed by passing through the post g' . Upon the rod L are secured at proper points the adjustable tappets M and N which project downwardly in the path of the cross-head F and are intended to be struck and moved thereby to a greater or less extent and at predetermined positions of the crosshead. As the crosshead moves to the right it comes into contact with tappet N and closes valve j' , again opening that valve when the weighty parts descend as described and restore the piston to the left end of the cylinder H . Upper and smaller cylinder J exercises the office of unlocking the screen-operating elements from their positions when the screen has been raised. Movable within the cylinder is the piston j^2 secured at the end of piston rod j^3 which passes through post g' and is guided therein. At its outermost end, being its right hand extremity as shown in the drawings, piston rod j^3 is arranged to encounter and turn a T-shaped catch P , which is pivotally supported between the twin lugs g^2 of bedplate G already described. The body of the catch P is provided with a shoulder or notch p , and, for purposes of explanation, the ends of the top or cross-piece of the T-shaped catch are marked, p' for the upper end lying in the path of piston rod j^3 , and p^2 for the lower end disposed in the path of an extended portion f' of crosshead F . The mode of operating my invention consists in applying the air by suitably turning the cock k , and at once shutting the air off and permitting that in the pipe k' to exhaust into the atmosphere, by way of the escape port k^2 of the cock. The position of piston j^2 and piston rod j^3 of upper cylinder J is immaterial. If the piston is at its leftward position within the cylinder, the pressure sends it and the rod to the right until it strikes the end p' of catch P and raises the catch. Let it be assumed that the other elements are as illustrated in Fig. 1, that is to say, in the positions assumed when the screen is down. Duct j leading from upper or lower cylinder is open and the air enters the lower and larger cylinder forcing its rod h' to the right, whereupon the extended portion f' of cross-head F comes into contact with the end p^2 of the catch P , and, overcoming the pressure in the smaller cylinder, turns down the notch p immediately behind the upper edge of the crosshead. Meantime, the screen has been raised as already explained, and the engagement of crosshead F and tappet N has closed the slide valve j' governing duct j . Now, the air escapes more or less rapidly from cyl-

inder H around the piston packing or by way of the small opening h^2 provided for that purpose, and the screen and connections would obviously descend were they not latched in their raised position by the engagement of crosshead F and the notch of catch P as shown in Fig. 3. It will be noted at this stage no pressure remains in the apparatus. There must necessarily be none, for the reason that should the full pressure remain in cylinder J , while it is cut off from cylinder H when the crosshead movement closes slide valve j' , in very little time the pressure in cylinder J would become dominant and operate its rod against the lessening force in the lower cylinder and release the screen when not desired. The office of valve j' is to prevent the too rapid escape of air from cylinder J . It will be understood that if the cylinder H , being charged with air under pressure from pipe k' , is at once exhausted after its piston h has forced piston j^2 fully to the left, sufficient pressure may still remain in pipe k' to force piston j^2 to the right, thereby accidentally releasing the catch.

The intentional release of the screen is accomplished by again momentarily charging cylinder J with air by operating the cock first to its supply position and then to its cut-off and exhaust position. Such action causes the piston rod j^3 to raise the notch of the catch quickly, releasing the screen and attachments and allowing them to fall. In either operation of setting or releasing there is no continuous supplying or constant application of air, and however careless or distraught the operator may be no air is wasted.

Having now described my invention and explained the mode of its operation, what I claim is—

1. In a signal light, the combination with the lamp, of a screen adapted to be raised and lowered in the path of the light, fluid-operated mechanism constructed and arranged to raise the screen, a catch device for holding the screen and mechanism in the raised position, and means for releasing the said catch device.

2. In a signal light, the combination with a lamp, of a screen adapted to be raised and lowered in the path of the light, fluid-operated mechanism constructed and arranged to raise the screen, an operating valve adapted to admit fluid to said mechanism and to discharge it, a catch device for holding the screen and mechanism in the raised position, and means for releasing the said catch device.

3. In a signal light, the combination with a lamp, of a screen adapted to be raised and lowered in the path of the light, a catch device, fluid-operated mechanism constructed and arranged to raise the screen and to engage the catch device whereby the screen is held in its raised position, an operating valve, a valve operated by said mechanism whereby

the fluid is cut off from the mechanism, said mechanism having an exhaust passage, and means for releasing the said catch device.

4. In a signal light, the combination with a lamp, of a screen adapted to be raised and lowered in the path of the light, fluid-operated mechanism constructed and arranged to raise the screen and provided with a passage normally open to the atmosphere, a catch device operated by the said mechanism whereby the screen is held raised, and means for releasing the catch device.

5. In a signal light, the combination with a lamp, of a screen adapted to be raised and lowered in the path of the light, a catch device, fluid-operated mechanism provided with an exhaust passage and constructed and arranged to raise the screen and the said catch device whereby the screen is held raised, means for shutting the fluid off from said mechanism, and means for releasing the said catch device.

6. In a signal light, the combination with a lamp, of a screen adapted to be raised and lowered in the path of the light, a catch device, fluid-operated mechanism constructed and arranged to raise the screen and the said catch device whereby the screen is held raised, and fluid-operated means for releasing the catch device.

7. In a signal light, the combination with a lamp, of a screen adapted to be raised and lowered in the path of the light, a catch device, fluid-operated mechanism constructed and arranged to raise the screen, the said catch device being arranged in the path of the said mechanism and adapted to be actuated thereby during a portion of the operation of the said mechanism whereby the screen is held raised, and fluid-operated means for releasing the catch device.

8. In a signal light, the combination with a lamp, of a screen adapted to be raised and lowered in the path of the light, a catch device, fluid-operated mechanism constructed and arranged to operate the screen and the said catch device whereby the screen is held raised, means whereby the said mechanism may be discharged, fluid-operated contrivances for releasing the catch device, and means for discharging the said contrivances.

9. In a signal light, the combination with a lamp, of a screen adapted to be raised and lowered in the path of the light, a catch device, fluid-operated mechanism constructed and arranged to operate the screen and the said catch device whereby the said screen is held raised, fluid-operated contrivances for releasing the catch device, means for discharging the said contrivances, and the said fluid-operated mechanism and contrivances being provided with means of communication whereby the fluid discharged from the said mechanism as the screen descends passes through the said contrivances.

10. In a signal light, the combination with a lamp, of a screen adapted to be raised and lowered in the path of the light, fluid-operated screen-actuating mechanism, a catch device arranged to be actuated by the mechanism whereby the screen is held raised, means for releasing the said catch device, the said mechanism and the said releasing-means being arranged to be simultaneously operated, the said mechanism being constructed to overpower the releasing-means through said catch device thereby preventing the catch from becoming released, and means for discharging said mechanism.

11. In a signal light, the combination with a lamp, of a screen adapted to be raised and lowered in the path of the light, fluid-operated screen-actuating mechanism, a catch device arranged to be actuated by the mechanism whereby the screen is held raised, fluid-operated catch-releasing means, the said mechanism and catch-releasing means being arranged to be simultaneously operated, the said mechanism being constructed to overpower the said releasing means through said catch device thereby preventing the catch from becoming released, and means for discharging said mechanism.

12. In a signal light, the combination with a lamp, of a screen adapted to be raised and lowered in the path of the light, fluid-operated screen-actuating mechanism, a catch device arranged to be actuated by the mechanism whereby the screen is held raised, fluid-operated catch-releasing means, the said mechanism and catch-releasing means being arranged to be simultaneously operated, the said mechanism being constructed to overpower the catch-releasing means through the said catch device thereby preventing the catch from becoming released, and the said mechanism having a permanently open exhaust passage.

13. In a signal light, the combination with a reciprocating element, of fluid-operated mechanism adapted to operate the said element, a catch device whereby the said element is held in a predetermined position, and means for releasing the said catch device, the said mechanism being arranged to overpower the catch-releasing means temporarily and prevent the releasing of the said element, and means for discharging the said mechanism.

14. In a signal light, the combination with a reciprocating element, of fluid-operated mechanism adapted to operate the said element, a catch device whereby the said element is held in a predetermined position, fluid-operated catch-releasing means, and means for admitting fluid to and discharging it from the said mechanism and catch-releasing means, said catch-releasing means being arranged to be actuated first.

15. In a signal light, the combination with an operating rod, of a screen-operating cyl-

- inder and fluid-operated mechanism adapted to operate the rod, a catch device whereby the rod may be held in a predetermined position, a catch-operating cylinder and fluid-operated catch-releasing means, the said mechanism being arranged to overpower the catch-releasing means and prevent the releasing of the rod, and means for discharging the screen-operating cylinder.
16. In a signal light, the combination with the operating rod, of a cylinder having a permanently open exhaust passage and fluid-operated mechanism adapted to operate the rod, a catch device whereby the rod may be held in a predetermined position, a cylinder and fluid-operated catch-releasing means, and an operating valve adapted to charge and to discharge the cylinder last mentioned.
17. In a signal light, the combination with the operating rod, of a cylinder having an exhaust passage and fluid-operated mechanism adapted to operate the rod, an operating valve a valve moved by the said mechanism and arranged to shut the fluid off said mechanism, a catch device whereby the rod may be held in a predetermined position, a cylinder and fluid-operated catch-releasing means, and means for discharging the last-mentioned cylinder.
18. In a signal light, the combination with the operating rod, of a cylinder having an exhaust passage and fluid-operating mechanism adapted to operate the rod, a catch device arranged to be operated by the said mechanism whereby the rod may be held in a predetermined position, a cylinder and fluid-operating catch-releasing means, the said catch device being constructed and arranged whereby the said mechanism overpowers the said catch-releasing means and prevents the release of the catch.
19. In a signal light, the combination with the operating rod, of a relatively larger cylinder having an exhaust passage and fluid-operating mechanism adapted to operate the rod, a catch device arranged to be operated by the said mechanism whereby the rod may be held in a predetermined position, a smaller cylinder and fluid-operated catch-releasing means, the said catch device being constructed and arranged whereby the said mechanism overpowers the said catch-releasing means and prevents the release of the catch, and means for discharging the smaller cylinder.
20. In a signal light, the combination with the operating rod, of a cylinder having an exhaust passage and fluid-operated mechanism adapted to operate the rod, an operating valve a valve moved by the said mechanism and arranged to shut the fluid off said mechanism, a catch device arranged to be operated by said mechanism whereby the rod may be held in a predetermined position, a cylinder and fluid-operated catch-releasing
- means, the said catch device being constructed and arranged whereby said mechanism overpowers the said catch-releasing means and prevents the release of the catch, and means for discharging the last-mentioned cylinder.
21. In a signal light, the combination with the operating rod, of a catch device, a rod-operating cylinder having an exhaust passage and rod-operating means, a catch-releasing cylinder, the two cylinders being connected by a communicating duct, means for admitting fluid to and for discharging the catch-releasing cylinder, said catch-releasing cylinder having a piston rod and a piston adapted by its movements to cover and uncover the mouth of said duct, the said piston rod and rod-operating means being adapted to move the catch device in opposite directions, and the said device being constructed and arranged whereby the rod-operating means overpowers the piston pressure in the said catch-releasing cylinder and shuts off the fluid from the rod-operating cylinder.
22. In a signal light, the combination with the operating rod, of a catch device, a rod-operating cylinder having an exhaust passage and rod-operating means, a catch-releasing cylinder, the two cylinders being connected by a communicating duct, one mouth of said duct opening near the head of said rod-operating cylinder and the other mouth opening at a distance from the corresponding head of the catch-releasing cylinder, means for admitting fluid to and for discharging the catch-releasing cylinder, said catch-releasing cylinder having a piston rod and a piston adapted by its movements to cover and uncover the mouth of said duct, the said piston rod and rod-operating means being adapted to move the catch device in opposite directions, and the said device being constructed and arranged whereby the rod-operating means overpowers the piston pressure in the said catch-releasing cylinder and shuts off the fluid from the rod-operating cylinder.
23. In a signal light, catch-operating mechanism comprising the combination with a catch, of a first cylinder having a piston and piston rod arranged to move the catch into its disengaged position, a second cylinder having a discharge passage and a passage in communication with the first cylinder, said second cylinder having also a piston and piston rod arranged to move the catch into its engaged position, and means for admitting compressed air to and for discharging it from the first cylinder.
24. In a signal light, catch-operating mechanism comprising the combination with a catch, of a first cylinder having a piston and piston rod arranged to move the catch into its disengaged position, means for admitting compressed air to and for discharging it from the said cylinder, a second cylinder having a

discharge passage and a piston and piston rod arranged to move the catch into its engaged position, the said second cylinder being provided with a passage arranged to admit compressed air to the cylinder, and a valve adapted to open and close the said passage.

In testimony whereof I affix my signature in presence of two witnesses.

ARTHUR W. COLLUM.
